UNITED STATES PATENT OFFICE.

MARY L. PATZKOWSKI, OF HOMESTEAD, OKLAHOMA.

LETTER-CARRIER'S FOLDING MAIL RECEPTACLE.

Application filed May 22, 1920. Serial No. 383,488.

To all whom it may concern:

Be it known that I, MARY L. PATZKOWSKI, a citizen of the United States, residing at Homestead, in the county of Blaine and 5 State of Oklahoma, have invented certain new and useful Improvements in Letter-Carriers' Folding Mail Receptacles; and I do hereby declare the following to be a full, 10 clear, and exact description of the invention, such as will enable others skilled in the art to which it appertains to make and use the same.

This invention relates to a folding mail receptacle used by letter carriers, and the 15 object is to provide a device which shall include a series of pockets formed on a flexible strip of canvas or the like, permitting the carrier to route his mail and deliver it by the use of one device, which in reality 20 serves as a distributing case and as a portable delivery pouch.

A further object is to provide a device 25 of the type indicated, which shall include a series of pockets formed on a flexible strip; with means for fastening the individual pockets, and means for securing the entire series, after the strip has been folded, in order to permit of the receptacle or pouch 30 to be carried or transported to the point where delivery is to be commenced.

A still further object is to provide a device 35 of the type indicated which shall include a strip of flexible material of suitable length, and of a width permitting one portion thereof to be folded over the remaining portion, longitudinally, for forming the pockets, a separate strip being attached in order to provide means for closing the upper ends of the pockets.

40 With the foregoing and other objects in view, the invention consists in the novel arrangement of the various elements contributing to the formation of the receptacles specified.

45 In the accompanying drawings—

Figure 1 is a plan view of the device in 50 extended position, the view being equivalent to a side elevation when the receptacle is in use for assorting or routing the mail.

Figure 2 is a view showing the pockets partly folded.

Figure 3 is a view showing the pouch or receptacle with the individual elements constituting separate pockets folded into a somewhat compact bundle for transportation.

Figure 4 is a section on the line 4—4 of Figure 1.

Figure 5 is a section on the line 5—5 of 60 Figure 3.

This receptacle is designed for the use of city carriers and also for carriers on rural delivery routes. In distributing the mail at the office prior to carrying it or transporting it to the point where delivery commences, the 65 receptacle may be attached to the wall of a room by means of the fastening devices provided for the purpose, and the strip may then be folded into compact form, the individual pockets being secured, and the 70 whole receptacle being fastened and locked, thus providing for the security of the contents under ordinary conditions.

A strip of flexible material, such as canvas, of any suitable length is provided, and 75 it is obvious that the receptacles may be made in various lengths in order to suit conditions, and further that the individual pockets may vary in size. The main strip is designated at 10, and for convenience, this 80 will be referred to as the rear wall of the receptacle, the front wall 12 being formed by folding over a portion of the strip in a longitudinal direction, and securing the edges by a line of stitching at each end as 85 shown at 14. The folded portion is further secured in any suitable manner, as by means of rivets 16 at points between the individual pockets and by stitching 14'.

In order to protect the contents of the 90 pockets, covers are provided, these being formed by attaching a single flexible strip 18 to the back 10, and cutting the strip in such manner that individual covers or closing devices 19 will be provided, the edges 95 of the portions slit or cut as indicated being protected by a binding or tape 20. Complementary securing elements are provided on the cover and on the adjacent walls of the pockets, and are designated 22 and 23. 100

The front of each pocket is provided with a transparent sheet of material, such as celluloid, stitched to the front wall of the pockets on three sides, leaving one side open for the admission of a label bearing the name of an 105 individual, the house or block number, or other designation.

Attached to the rear wall 10 are loops 25 through which strap 26 passes, this strap being designed to pass around the series of 110 pockets, when the strip is folded into a somewhat compact bundle. Connected with the

upper portion of rear wall 10 is a cord for supporting the device while the mail is being placed in the pockets, it being convenient to suspend the entire receptacle 5 along a wall, in many instances. This cord designated 28 may also be used as a shoulder strap, if delivery is to be made by letter carriers who cover their route on foot. The cord passes through eyelets 30 and connected with the opposite end of this cord are securing devices 31 each comprising a central shank portion, and ring members at each end of the shank. One of these ring members is connected directly with the cord, and 10 the other may be engaged by a hook or the like placed in the wall.

It is obvious that the individual pockets may be locked if desirable and that these 20 separate pockets may be used for the mail of a given individual or concern or for two or more individuals, as indicated by the labels on the front. It is also obvious that the details of construction may be varied within the scope of the appended claims.

25 Having thus described my invention, what I claim is:—

1. A device of the class described having a body with a front wall and a rear wall extending above the same to form a suspending portion, the front and rear walls being connected and providing a plurality of pockets, a closure flap for the pockets secured to the rear wall and movable against it to expose the contents of the pocket, the 30 device being foldable intermediate the 35

pockets and across said wall and a flexible suspending member on the suspending portion passing loosely through openings therein adjacent the lines of folding for the purpose specified. 40

2. A device of the class described comprising a plurality of compartments, a suspending wall extending above the compartments and a closure means for the compartments extending from said wall and intermediate 45 its horizontal edges and movable against it to expose the contents of the compartments, each of said compartments being foldable on the adjacent compartments, and means to hold said compartments in folded condition. 50

3. A device of the class described comprising a rear and a front wall, said rear wall extending above said front wall and forming a suspending wall, said wall being connected at spaced intervals to form a plurality of 55 compartments, loops carried by said walls and positioned in the rear of said rear wall, means fastening said loops to said walls and said means connecting said walls, all of the compartments being foldable each on the adjacent compartments, and a flexible element passing through the loop and serving to hold the device in folded condition. 60

In testimony whereof I affix my signature in presence of two witnesses.

MARY L. PATZKOWSKI.
